(57) CLAIM

The ornamental design for a box for game pieces as shown and described.

DESCRIPTION

1. Box for game pieces

1.1: Perspective

1.2: Front

1.3: Back

1.4: Left

1.5: Right

1.6: Top

1.7: Bottom

Box for game pieces in the shape of a flat cuboid with a groove along the center of both longitudinal sides.

The broken lines in the drawings depict portions of the box for game pieces that form no part of the claimed design.

1 Claim, 7 Drawing Sheets
